Attorneys

UNITED STATES PATENT OFFICE.

HARRY MAINO, OF JACKSON, MICHIGAN.

JACK.

Application filed March 19, 1923. Serial No. 626,029.

To all whom it may concern:

Be it known that I, HARRY MAINO, a citizen of the United States of America, residing at Jackson, in the county of Jackson 5 and State of Michigan, have invented certain new and useful improvements in Jacks, of which the following is a specification, reference being had therein to the accompanying drawings.

10 This invention relates to lifting jacks for automobile and other uses, and it has for its principal object to provide a device which may be quickly set to any desired position with respect to the load and then operated by a crank or equivalent means for lifting the load.

Another object of the invention is the provision of a form of base whereby the height of the jack may be quickly varied within 20 wide limits to adapt the jack for high or low axles or other loads.

Other and further objects will appear in connection with the accompanying specification, reference being had to the drawings forming a portion thereof, in which—

Figure 1 is a vertical section of a preferred embodiment of the invention;

Fig. 2 is a section at right angles to that of Fig. 1, and

30 Fig. 3 is a horizontal section on the line III—III of Fig. 1.

The base of the jack is represented by the numeral 1, and preferably consists of a hollow casting having recesses 2 at each side to receive and to guide the lugs 3 formed upon a hollow barrel 4. Near the upper end of the base member 1 are formed a pair of openings 5, 5, adapted for the reception of a U-shaped supporting member 6, the parallel arms of which are of a size adapted to be inserted between the lugs 3 to hold the barrel 4 in any desired position of vertical adjustment.

An arm 7 preferably formed as an integral part of the barrel 4 extends outward from one side of the barrel and upward, being formed with a cylindrical perforation 8 which is in line with a corresponding perforation 9 formed within the upper portion of the barrel, the perforations 8 and 9 acting as bearings for a shaft 10. Upon the shaft 10 is secured a bevel gear 11 which engages a bevel gear 12 internally screw-threaded to receive a buttress screw 13 arranged axially of the barrel 4. Upon the

lower end of the screw 13 is secured a guide block 14 which is of a suitable size to slide freely within the non-circular hollow interior of the barrel 4 to prevent rotation of the screw 13. Within the upper end of the barrel 4 is formed a recess 15 which receives a thrust bearing 16 upon which rests the lower face of the bevel gear 12. A load carrying head or plate 17 is mounted upon the upper end of the screw 13. The outer end of the shaft 10 is squared or otherwise shaped at 18 to receive a crank or other form of operating means by which the shaft 10 may be rotated to cause rotation of the gears 11 and 12.

A sheet metal plate 19 is secured as by rivets 20 upon the lower end of the base 1 to close the opening and thus to prevent dirt, stones or other matter from interfering with the free movement of the barrel 4. A plate of sheet metal will obviously be less likely to break than a cast metal base of corresponding thickness. The use of sheet metal aids in securing lightness while providing the necessary strength.

The operation of the device will be obvious from the description. The jack will be placed in position beneath the axle or other load to be lifted, and with the U-shaped support 6 withdrawn out of engagement with the lugs 3, the barrel 4 may be lifted, using the cam 7 as a handle, until the head 17 engages the object to be lifted. The support 6 will then be slid beneath the lug 3 which lies above the opening 5, the barrel 4 being raised or lowered to permit the insertion of the support 6 entirely across the channels 2. The operating means will then be applied to the non-circular end of the shaft 10 and rotated to cause the gear 12 to rotate about the screw 13 and thereby lift the screw and its head 17 to engage the load and raise it to any desired point. In this manner it will be seen that the vertical adjustment of the barrel may be readily accomplished to vary the height of the jack rapidly within comparatively wide limits without affecting the operation of the lifting screw so that the whole length of the screw may be available for lifting after the barrel has been adjusted to the greatest available height beneath the load to be lifted.

While I have described a specific device embodying my invention, it will be obvious that many changes may be made in the

form, proportion, details of construction and arrangement of parts without departure from the principle involved or sacrificing any of its advantages. It is therefore to be understood that the invention is not limited to the specific details shown, but it is claimed in any of its forms or modifications within the legitimate and valid scope of the appended claim.

10 I claim:—

A jack comprising a hollow base having walls thereof provided with oppositely arranged longitudinal grooves, a barrel having spaced lugs slidable in the grooves of the hollow base, a horizontally disposed U-shaped support in the upper end of said base and having parallel portions adapted to be placed between the barrel lugs whereby the

barrel may be supported to various positions of adjustment longitudinally of the base, an arm on said barrel extending out of said base to facilitate shifting said barrel in said base, a screw slidable longitudinally of the barrel, a rotatable member in screwthreaded engagement with said screw and supported by said barrel, and means supported by said arm and barrel for rotating said member to cause movement of the screw longitudinally of the barrel.

In testimony whereof I affix my signature in presence of two witnesses.

HARRY MAINO.
